CLAIM

The ornamental design for a screw juicer, as shown and described.

DESCRIPTION

FIG. 1 is a perspective view of the screw juicer showing the design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side view thereof;

FIG. 7 is a right side view thereof; and,

FIG. 8 is a perspective view of the screw juicer after a certain part is rotated.

The broken lines are for the purpose of illustrative purposes, showing the environment in which the design is used, and forms no part of the design.
